UNITED STATES PATENT OFFICE

135,104

DESIGN FOR A PORTABLE SOUND AMPLIFICATION UNIT

Walker C. Cottrell, Jr., Richmond, Va.

Application May 4, 1942, Serial No. 106,788

Term of patent 7 years

To all whom it may concern:

Be it known that I, Walker C. Cottrell, Jr., a citizen of the United States, residing in the city of Richmond, in the State of Virginia, have invented a new, original, and ornamental Design for a Portable Sound Amplification Unit, of which the following is a specification, reference being had to the accompanying drawings, forming a part thereof, wherein:

Figure 1 is a top plan view of a portable sound amplification unit showing my new design;

Figure 2 is a side elevational view thereof;
Figure 3 is a front elevational view thereof;
and

Figure 4 is a rear elevational view thereof.
The characteristic features of my design are shown in full lines.

I claim:

The ornamental design for a portable sound amplification unit, as shown and described.

WALKER C. COTTRELL, JR.
